CHARLES LALOR BURDICK, OF NEW YORK, N. Y., ASSIGNOR TO GUGGENHEIM BROTHERS, OF NEW YORK, N. Y., A COPARTNERSHIP.

HEATING HIGH-TEMPERATURE APPARATUS.

Application filed June 25, 1926. Serial No. 118,413.

This invention relates to high temperature apparatus such as furnaces and more particularly metallurgical furnaces. The invention has for its object the provision of improved electric heating for such high temperature apparatus, and more particularly the invention aims to provide improved electric heating for metallurgical furnaces of the multiple hearth type.

10 Heretofore, one of the chief difficulties with electric heating elements for metallurgical furnaces and the like has been their inaccessibility so that when replacements were required, it has been necessary to interrupt the 15 operations of the furnace. Moreover, the usual materials of which heating elements are made will not withstand the corrosive action of certain gases and materials introduced or generated within the furnace.

20 The present invention contemplates the provision of an improved electric heating unit for metallurgical furnaces, and more particularly for circular furnaces such as the multiple hearth furnaces. In accordance 25 with the invention the electric heating or resistance element is enclosed within a protective tube and suitably mounted within the furnace. The arrangement of support is such that in case any replacement is required, 30 either the entire tube and element may be taken out and another complete unit put in its place, or if only the heating element requires renewal, the element may be withdrawn from the tube and another put in its place. A plurality of these heating units in the same furnace may be connected electrically in series 35 or in parallel, and the renewal, in whole or in part, of a single unit can be easily made without interfering with the operation of the 40 furnace.

The heating units of the invention are particularly applicable to multiple hearth furnaces, such as the Wedge or MacDougal furnaces. In these furnaces, the hearths are so 45 arranged that there is no opportunity for repair work within the furnace while operating at high temperatures and for this reason electrical heating has not heretofore been considered practicable.

50 The novel features of the invention will be best understood from the following description taken in conjunction with the accompanying drawing, in which

Fig. 1 is a sectional elevation of a single 55 hearth or heating chamber in a multiple

hearth furnace provided with the improved electrical heating means of the invention;

Fig. 2 is a cross section of the furnace of Fig. 1 taken generally along the section line A—A; and

Fig. 3 is a cross section of the improved electric heating unit of the invention.

The furnace illustrated in the accompanying drawing has an outer cylindrical metal shell 1 and an inner structure or lining 2 of fire brick or other appropriate heat-refractory material. The furnace has a plurality of superposed hearths, of which two are shown in Fig. 1 of the drawing. A vertically disposed shaft 3 extends through appropriate central openings in the hearths and is adapted to be rotated by an appropriate source of power (not shown).

The shaft 3 carries radially disposed arms 4 positioned above each of the hearths. 75 Plows or scrapers 5 are attached to the arms 4. The plows 5 are arranged to move the charge on adjacent hearths in opposite directions towards appropriate discharge openings, such as 6 and 8 in Fig. 1.

In accordance with my present invention, a plurality of electric heating units 9 are radially disposed in each heating or working chamber 7 of the furnace, and hence above each of the superposed hearths. The heating units extend through appropriate openings in the cylindrical side wall of the furnace and are supported within the furnace by hangers or brackets 10. A removable bushing or other appropriate packing means 13 seals the space between the outer end of each heating unit and the furnace wall.

The heating unit comprises a protective tube or casing 14 within which is appropriately mounted the electric heating element 16. 95 The heating element is supported within the protecting tube by insulating discs 15, of porcelain, lava rock, asbestos fiber, or other appropriate material. The terminals 11—12 of the heating element extend beyond the open end of the tube 14 and are appropriately connected to the source of electric energy. In Fig. 2 of the drawing, the six heating elements 16 are electrically connected in series and to the source of electric energy (not 105 shown).

The heating element 16 is spaced from the interior walls of the enclosing tube 14. The element is so constructed as to generate a progressively increasing amount of heat from 110

the center towards the periphery of the heating chamber. In a circular furnace, if the heating element throughout the length of the protecting tube be of uniform construction, 5 more heat will be generated and dissipated per square foot of hearth area near the center of the furnace than at the circumference. In order to obviate this difficulty and to maintain a uniform temperature over the entire 10 hearth, the number of coils per foot of the heating element are in proportion to the distance from the center of the furnace. For example, a heating element supported radially within a twenty-foot diameter furnace 15 would have ten coils or turns of resistance wire or ribbon per foot at the circumference and five turns per foot at a distance of five feet from the center and three turns at a distance of three feet from the center. The 20 actual number of turns or coils will vary with the amount of heat, size of wire, temperature required, etc., and the example just given is merely to show that the area to be heated under the element is proportional to the distance from the center of the furnace and that 25 the variation in the number of turns or coils will vary in this same proportion or in an otherwise compensated manner.

The wire or ribbon swerving as the resistance or heating element 16 is so mounted that no part of it touches the protecting tube 14. The material for the heating elements may be of any of the standard metals or alloys as, for instance, nichrome wire or ribbon. The 30 protecting tubes are made of any material that will withstand the temperature and the harmful effect of gases, dust, and other materials present in the heating chambers during the operation of the furnace. Tubes made 35 of 30% ferro-chrome have been found satisfactory for use in the reduction of certain metallic oxides, the metals from which react or alloy with iron or copper etc. The tubes 40 may also be made of quartz, carborundum, and other appropriate refractories. 45

The heating units of the invention are of particular advantage in multiple hearth furnaces, as well as in other furnaces in which the hearth is circular. Thus, the heating 50 units are conveniently supported within the furnace and may be conveniently removed, in whole or in part, when replacements are necessary, without interfering with the operation of the furnace. Moreover, the heating 55 elements are of such construction and so arranged that the circular hearth is uniformly heated over its entire area by the heat generated in and dissipated to the hearth by radiation and by conduction through gases. The

invention permits the use of the multiple 60 hearth furnace in operations for which it was heretofore unsuited, as, for example, the reduction of metallic oxides, such as tin oxide, either by gaseous reduction or by solid reducing agent. 65

I claim:

1. The combination with a high temperature apparatus having a heating chamber of circular section of electric heating units comprising a plurality of elongated electric heating elements each radially disposed in said chamber and of such construction that the amount of heat generated by said element progressively increases from the center towards the periphery of said heating chamber. 75

2. The combination with a multiple hearth furnace having substantially circular heating chambers, of a plurality of electric heating units radially disposed in each of said chambers, each of said units comprising an electric heating element mounted within a protective casing of heat refractory material, the heating element being removable from its protective casing and from the furnace and the heating unit being removable as a 80 whole from the furnace without interrupting the operation thereof. 83

3. The combination with a multiple hearth furnace having substantially circular heating chambers, of a plurality of electric heating units radially disposed in each of said chambers, each of said units comprising an electric heating element mounted within a protective casing of heat-refractory material, the heating element being removable 90 from its protective casing and from the heating chamber and the heating unit being removable as a whole from the heating chamber without interrupting the operation of the furnace, said heating elements being of such construction that the amount of heat dissipated therefrom progressively increases from the center towards the periphery of the heating chamber. 95

4. A heating unit comprising a helical coil of gradually increasing pitch from one end to the other mounted within a casing of heat refractory material in spaced relation to the walls of said casing. 105

5. A furnace comprising a series of superposed heating chambers, and a plurality of heating elements mounted within each chamber adjacent the top thereof and extending from points adjacent the side walls to the centrally portion of the chamber. 110 115

In testimony whereof I affix my signature,

CHARLES LALOR BURDICK.
